UNITED STATES PATENT OFFICE.

GEORGE MORGAN, OF BINGHAMTON, NEW YORK.

GUARD FOR BUFFING WHEELS.

Application filed September 2, 1921. Serial No. 497,856.

To all whom it may concern:

Be it known that I, GEORGE MORGAN, a citizen of the United States, and a resident of Binghamton, in the county of Broome and State of New York, have invented a new and Improved Guard for Buffing Wheels, of which the following is a full, clear, and exact description.

This invention relates to improvements in shoe machine guards, an object of the invention being to provide a guard for the buffing wheels of shoe machinery and the like, which can be conveniently attached to the machine and which will function to prevent scarring of uppers, over-counters, and back stays of shoes while buffing the heels of the shoe.

A further object is to provide a guard of the character stated which is capable of movement relative to the buffing wheel to allow the sandpaper or other surface of the wheel to be removed and replaced as occasion may require.

A further object is to provide an improved mounting for the guard which permits of adjustment thereof to compensate for different heights of shoe heel on which the operator is working.

A further object is to provide a guard of the character stated which functions as a guide and which not only improves the operation of buffing the heel because of the fact that it prevents injury to other parts of the shoe, but because of the fact that the guard acts as a guide and permits a more rapid operation than is possible without the same.

With these and other objects in view the invention consists in certain novel features of construction, and combinations and arrangements of parts as will be more fully hereinafter described and pointed out in the claims.

In the accompanying drawings—
Figure 1 is a fragmentary view partly in elevation and partly in longitudinal section illustrating my improved guard in operative position relative to the buffing wheel of the shoe machine or the like.

Figure 2 is a view in end elevation of Figure 1.

Figure 3 is a view in sectional elevation on the line 3—3 of Figure 1.

Figure 4 is a fragmentary view in transverse section on the line 4—4 of Figure 1. For purposes of illustration, I have

indicated a fragmentary portion 1 of a shoe machine frame in which a shaft 2 is supported and on said shaft 2 a buffing wheel 3 is secured. This buffing wheel 3 is of the ordinary type having a removable outer strip or sheet of sandpaper 4 or other similar material, which is removably connected to the wheel with the ends thereof clamped in a slot or recessed portion 5 as is common in the art, so that when the surface of the wheel becomes worn, the strip or sheet can be replaced.

6 represents a bracket which is provided with a supporting arm 7 adapted to be secured to the frame 1 of the machine by means of a pair of screws 8, although it is obvious that the bracket might be otherwise secured to the frame. This bracket 6, which is located in a plane below the buffing wheel 3, is made with a pair of aligned bearings 9 and 10 supporting a rod 11.

12 represents a hand wheel which constitutes an integral or fixed portion of an adjusting sleeve 13, the latter having rotary mounting in the outer portion of bearing 9 and held against longitudinal movement by means of a screw 14 which projects through the bearing 9 and into an annular groove 15 in the sleeve.

The sleeve 13 is made with an internally screw threaded bore 16 which receives a screw threaded extension 17 on the rod 11 so that when the hand wheel 12 is turned, it will compel the longitudinal adjustment of the rod 11 in the bearings 9 and 10 for a purpose which will hereinafter appear.

18 represents my improved guard which is in the form of a curved arm adapted to be positioned close to the periphery of the buffing wheel and having a straight or flat face 19 against which the heel of the shoe is to be placed to limit the movement of the heel transversely of the periphery or surface of the buffing wheel 3. This guard 18 has a hub which is bifurcated and provided in its bifurcated portion with aligned openings 20, which receive the rod 11 between the bearings 9 and 10 and permit a pivotal movement of the guard on the rod. A collar 21 is located on the rod 11 within the bifurcated portion of guard 18 and this collar is secured to the rod 11 by means of a jam screw 22 locking the collar and the rod together, preventing independent movement thereof in any direction. A finger 23 is formed on the collar 21 and engages un-

der the bracket 6 so as to prevent turning movement of the rod in one direction.

This collar 22 is formed in its upper portion with a socket 24 into which a spring pressed pin 25 carried by the guard 18 is adapted to fit so that when said pin is in the socket, the guard will be held in its normal operative position. When the spring pressed pin is withdrawn from the socket 24, the guard can be swung downwardly to the dot and dash line position shown in Figure 2, so that the cover of the buffing wheel can be changed and not interfere with the operation of such changing.

15 The operation is as follows: By reference particularly to Figure 1, it will be noted that the straight or flat face 19 of the guard 18 is parallel with the edge of the buffing wheel 3 and is spaced from said edge 20 a distance equal to the height of the heel to be buffed. Hence, an operator can quickly buff the heels and shoes by placing the bottoms of the heels against the guard 18 and the edges of the heels against the surface of 25 the buffing wheel so that said heels can be properly and quickly buffed without any danger of injuring other portions of the shoe. As the height of shoe heels varies, it is necessary to provide a lateral adjustment 30 for the guard and the hand wheel 12 and sleeve 13 having screw threaded engagement with the extension 17 of rod 11 permit this adjustment. When the hand wheel 12 is turned, it will cause a longitudinal movement of the rod 11 and as the collar 21 in 35 the bifurcated portion of the guard 18 will compel the guard to move with the rod 11, said adjustment can be had.

40 When it is desired to change the surface of the buffing wheel, it is simply necessary to withdraw the spring pressed pin 25 from the socket 24 and the guard can be swung downwardly, as shown in Figure 2, and after the buffing wheel is properly surfaced, the guard can be swung back to operative position and the spring pressed pin 25 will automatically engage in the socket 24 and hold the guard in proper operative position.

45 50 Various slight changes might be made in the general form and arrangement of the parts described without departing from the invention, and hence I do not limit myself to the precise details set forth, but consider myself at liberty to make such changes and alterations as fairly fall within the spirit and scope of the appended claims.

I claim:

55 60 65 1. A guard for buffing wheels, comprising a bracket support, a pair of aligned bearings on the bracket support, a rod in said bearings, an adjusting sleeve in one of the bearings and secured against longitudinal movement, said sleeve and rod having screw threaded engagement whereby rotary

movement of the sleeve imparts longitudinal movement to the rod, a blade-like member having a perforated bifurcated portion receiving the rod and located between the bearings, and a collar on the rod in the bifurcated portion of the blade-like member. 70

2. A guard for buffing wheels, comprising a bracket support, a pair of aligned bearings on the bracket support, a rod in said bearings, an adjusting sleeve in one of the bearings and secured against longitudinal movement, said sleeve and rod having screw threaded engagement whereby rotary movement of the sleeve imparts longitudinal movement to the rod, a blade-like member having a perforated bifurcated portion receiving the rod and located between the bearings, a collar fixed to the rod and located in the bifurcated portion of the blade-like member, said collar having a socket 75 80 85 therein, and a spring pressed pin carried by the blade-like member and adapted to engage in the socket to hold the blade-like member in operative position, but permits the blade-like member to be swung on the rod out of operative position. 90

3. A guard for buffing wheels, comprising a bracket support, a pair of aligned bearings on the bracket support, a rod in said bearings, an adjusting sleeve in one of the bearings and secured against longitudinal movement, said sleeve and rod having screw threaded engagement whereby rotary movement of the sleeve imparts longitudinal movement to the rod, a blade-like member having a perforated bifurcated portion receiving the rod and located between the bearings, a collar fixed to the rod and located in the bifurcated portion of the blade-like member, said collar having a socket 95 100 105 therein, a spring pressed pin carried by the blade-like member and adapted to engage in the socket to hold the blade-like member in operative position, but permits the blade-like member to be swung on the rod out of operative position, and a finger on the collar 110 engaging under the bracket and preventing turning movement of the rod in one direction.

4. A guard for buffing wheels comprising a blade-like member which is curved to be adaptable to the periphery of a buffing wheel, a hub extending to one side of said member, means passing through the hub and by which the blade-like member is supported in front of the working face of the buffing wheel, means by which the supporting means is carried, and means embodied in said carrying means for moving the supporting means and thereby adjusting the blade-like member across said working face. 115 120 125

5. A guard for buffing wheels comprising supporting means, means providing bearings by which the supporting means is carried, means swivelled on the carrying means 130

for moving the supporting means in the direction of the axis of a buffing wheel, a blade-like member having a hub located on the supporting means and situated in front of the working face of said wheel to be engaged by one side of an object to be buffed, means fixing the location of said hub on the

supporting means, and means associated with both the hub and said fixing means whereby the blade-like member may be locked in an operative position and released for the occupancy of an inoperative position.

GEORGE MORGAN.
